SCAFFOLD

Filed Dec. 18, 1922. 2 Sheets-Sheet 2

By

O. M. Haughton
Attorney

UNITED STATES PATENT OFFICE.

WILLIE R. YOUNG, OF BAINBRIDGE, GEORGIA.

SCAFFOLD.

Application filed December 18, 1922. Serial No. 607,650.

To all whom it may concern:

Be it known that I, WILLIE R. YOUNG, a citizen of the United States, residing at Bainbridge, in the county of Decatur and State of Georgia, have invented certain new and useful Improvements in Scaffolds, of which the following is a specification.

This invention relates to improvements in scaffolds and it comprises a supporting member arranged for attachment to the wall of a building in proximity to a window, such member being provided with means for holding a bracket or the like in any one of a number of different vertical positions, a bracket or the like arranged for temporary attachment to said member in one of the positions, and a collapsible platform arranged for attachment to a sill of a window of a building, such platform comprising a plurality of connected members which may be folded one upon another in such position to provide a support in line with the bracket attached to the vertical member in one position and which may be unfolded and secured in unfolded position to provide a second support in alinement with the first bracket or support connected to the vertical member in a second position, whereby a plank or the like may be used to bridge the space between the said platform and the bracket or support attached to the vertical member in their different positions; all as more fully hereinafter set forth and as claimed.

In the art to which this invention relates the provision of simple, inexpensive and easily handled scaffolding which may be temporarily attached to a building without disfiguring the same for the purpose of washing the walls, painting the walls and washing the windows has long been a desideratum. One of the objects of my invention is the provision of such a scaffold.

In the accompanying drawings I have shown one form of a special embodiment of my invention, in the several views of which similar reference numerals indicate corresponding parts. In the drawings

Fig. 1 is a perspective view of a building showing my scaffold applied thereto in one position;

Fig. 2 is a vertical segmental section view partly in elevation through the window showing the window support in one position;

Fig. 3 is a view similar to Fig. 2 showing

the window support in the raised or elevated position; and

Fig. 4 is a detailed perspective segmental view of the removable vertical wall supporting member.

Referring to the drawings, 1 indicates the vertical supporting member (hereinafter called the wall supporting member) which is shown in right angled form arranged to fit the corner of the building. This wall supporting member may be made in other shapes, as will be apparent, when it is to be used at other positions than at corners of buildings. The wall supporting member 1 is provided on each side with a series of spaced keyholes 2 shown here as rectangular in shape and having downwardly extending slots 3 for the purpose of engaging the shank of the bracket hereinafter described. The sides of the wall supporting members are also provided with a plurality of hooks 4 arranged for engagement with studs, nails or the like 5 which may be driven into the wall of the building.

The bracket designated as a whole by 6 (hereinafter referred to as the wall bracket) comprises two members 7 and 8 arranged at approximately a 45° angle. The top member 7 is provided at its end with a locking portion comprising the square head 9 and the shank 10, the head 9 being arranged for insertion in the square hole 2 of the wall supporting member so that the shank 10 may be lowered in the slot 3 of such member. When the wall bracket is secured in position in the wall supporting member as described, the member 7 of the wall bracket will extend outwardly from the wall of the building at substantially a right angle. The other member 8 of the wall bracket will then be in position to engage the wall support at another locking point, this member 8 of the wall bracket being also provided with locking means 9 and 10.

Plank 11 may be supported at one end on the horizontal member 7 of the wall bracket and on the other end by the window bracket, now to be described.

The window bracket comprises a base member 12 which is provided at one end (the end extending inside the room) with a clamp 13 provided with a right angled extension 14 adapted to fit under the sill of the window inside the room, such clamp being held in position by means of the bolts 15 and 16.

winged nuts 16. The base member 12 finds support on the window sill 17 and extends outwardly therefrom. It is, in addition to being supported inside the room by the clamp described, also braced by means of the brace designated as a whole by 18. This brace is hinged by means of the hinges 19 to the end of the base member 12 and the brace may comprise a plurality of arms having at their lower extremity a squared block-like member 20 which engages the outer face of the building; the whole construction being such as to rigidly hold the base member 12 against movement and vibration. The brace 18 may be secured in bracing position by means of the hook 21 pivoted at 22 to the base member and hooking over stud 23 on the brace.

There is also attached to the base member 12 at its lower extremity, by means of the hinge 24, a foldable board 25 provided with a pivoted hook 26 and this board in turn is provided at its end with a hinge 27 carrying a second board 28 provided with the stud 29 over which the hook 26 may be placed. The second board 28 in turn is provided at its end with the hinge 30 and with the stud 31, the hinge 30 carrying a third board 32 provided with the pivoted hook 33 arranged to engage the stud 31. These three boards just referred to may be unfolded and arranged in the form of a rectangle as shown in Fig. 3 so that the board 28 is elevated a considerable distance above the base member 12 and in such position forms an elevated support for the end of the plank 11. When this collapsible platform arrangement is used in the elevated position the wall bracket 6 may be attached in a corresponding elevated position on the wall supporting member. The boards 25 and 32 may be of any length desired, but I have found in practice that if they be of a length sufficient to elevate the board 28 about half way up the window, not only can the entire window be washed by one standing on the board in its lowered and elevated position, but that the plank 11 when placed in these two positions makes the wall of the building accessible between two windows and thereby makes the entire wall of the building accessible because the window support may be used on the next higher or lower window.

In order that the board 28 may be suitably braced when in elevated position, I provide it with an eye 34 and I provide the base member with an eye 35. The detachable brace 36 is angled at its ends and provided with the slots 37 and 38 arranged to fit over the eyes 34 and 35. In effect this brace 36 is a double hasp. The bolt or the like 39 may be temporarily in the eyes to hold the double hasp in position.

The operation of the scaffold is obvious

from the foregoing. The board 28 may be placed in elevated or lowered position, as shown respectively in Figs. 3 and 1, in which positions it serves as a support for one end of the board 11. Wall bracket 6 may be placed in any one of a plurality of positions on the wall supporting member 1 to accommodate the other end of the plank and the whole building may be washed or painted, all portions being accessible through this arrangement.

The scaffold board 11 adjacent each end is provided with a series of openings 11', in which wooden pegs may be driven to prevent any sliding of the board on the wall scaffold and the window scaffold.

What I claim is:

1. Scaffolding apparatus comprising a vertical member arranged to be secured in vertical position on the wall of a building and having a plurality of vertically spaced means for the support of a bracket, a wall bracket arranged to be carried by said member in any one of said positions, a window bracket provided with means for securing it to the sill of a window and provided with collapsible members one of which is capable of being positioned in two different vertical positions, and a board bridging said wall bracket and said window bracket and engageable with said last named member in either of its vertical positions.

2. In a scaffolding apparatus a window bracket comprising a substantially flat member provided at one end with means for securing it to a sill of a window and having at its other extremity a hinged member arranged to be positioned at right angles to the said flat member and carrying at its extreme end a similar member arranged to be positioned parallel to the said flat member and at a distance therefrom corresponding to said other member, means for holding the said members in such position and means for holding said members in assembled position whereby there is provided a support in proximity to the window at about the level of the window sill or at a level somewhat above.

3. A scaffolding apparatus comprising a body portion having a downwardly and inwardly extending portion adapted to extend under the inner edge of a sill of a window, a hinged member carried at the outer end of the said bottom portion and arranged to engage a wall of a building, means for locking the members in operative position, and a collapsible platform carried by the body portion adjacent its outer end, said platform comprising three sections hinged together, two of said sections being supported by said body portion when the platform is in raised position.

4. A scaffolding apparatus comprising a body portion adapted to be secured to a sill

- of a window, a platform comprising a series of sections hinged together, a hinged connection between one of the sections and the outer end of the said body portion, 5 means for holding the platform in raised position and means for allowing the platform to be folded flat upon the body portion, the said platform being of rectangular cross-section when in raised position.
- 10 5. A scaffolding apparatus, comprising a wall supporting member composed of an angle iron, means for securing the same to the corner of a building, a bracket adapted to be vertically and adjustably supported by 15 said angle iron, a window bracket provided at one end with means for securing it to the sill of a window of a building, and at its other end with hinged sections adapted to assume positions in different horizontal 20 planes, means to lock said hinged sections in any of their different positions, and a scaffold board bridging said bracket and window scaffold and engageable therewith in either of its said positions, the said wall 25 bracket being so adjustable that the scaffold board can be maintained in horizontal position regardless of the position of the window bracket.
6. A scaffolding apparatus, comprising a 30 wall bracket formed of an angle iron, a bracket vertically adjustably supported by the said angle iron, and a window bracket provided with means for securing it to the sill of a window, a collapsible platform carried by the window bracket, and a board engageable with said window bracket in any 35 of its vertical positions, and bridging said brackets whereby the board may be supported at different levels.
- 40 7. A scaffolding apparatus, comprising a wall bracket consisting of a member having means for securing it to the wall, a bracket vertically adjustably supported thereby, a window bracket provided with means for 45 securing it to the sill of a window of a building, a collapsible support carried by the window bracket, and a board bridging said
- brackets whereby the same may be supported at different levels the board being engageable with said window bracket at any of its 50 different levels.
8. A scaffolding apparatus, comprising a wall bracket consisting of a member having hooks carried thereby for securing it to the wall of a building, keyhole slots arranged 55 therein, a bracket having headed members whereby it is supported at different levels by the wall bracket, a window bracket provided with means for securing it to the sill of a window, a collapsible support carried by the 60 window bracket, and a scaffold board bridging said brackets whereby it may be supported at different levels the board being engageable with said window bracket at any of its 65 different levels.
9. Scaffolding apparatus for buildings having windows, comprising a support arranged to be secured at a window substantially in line with the sill thereof, and provided with means permitting elevation of a 70 part thereof so that the elevated part may be positioned above the sill, a bracket and means for securing said bracket to the building at different vertical points to one side of the window, a scaffold board carried by the 75 two sets of supports whereby the first support at the window, in either position, and the adjustable bracket in line with the window, may serve to support the bridging scaffold board at different heights along the face 80 of the building corresponding to the adjustment of the first window support.
10. A scaffolding apparatus comprising a body portion adapted to be fastened at one end to the sill of a window, a collapsible 85 platform mounted upon said body portion, said platform comprising a plurality of sections hinged together and adapted to assume positions at right angles to each other when in raised position, and means to lock said 90 sections in raised position.

In testimony whereof, I have hereunto affixed my signature.

WILLIE R. YOUNG.
